John Bottom & Dauphin Penn 6673X

Collins Patent

In Schedule referred to in these Collins Patent and making part of the same Containing a description in the words of the said John Bottom, summary of his improvement in the mode of making and constructing a Bell for separating the Chaff in Corn Seed Mills Specified in the words following this. This improvement in the Bell is made of thin boards, say five eighths of an inch thick & from two to twelve feet long. It may be made round or any number of squares but say 8 squares is deemed the best, with a shaft through the the centre & bound in with the arms past through each shape at one foot from each end.

The bell is to have three ribs, or grooves around in the outside the two outer ends, one foot from each end, & the other in the centre. The bell can be made any size from one foot and one foot to three feet diameter, & say each one of the six squares about one foot four inches to one foot six inches wide. & the outside, covering a board to be forced into & a half square with a hole five eighths or three quarters of an inch to let the shaft pass through & the chaff project at the end of said Bell.

And said Bell can be turned by a shaft strong enough to sustain at the rate of about twenty five or thirty revolutions per minute. The lever or tail end to be placed about six inches back from the head and to project so as to cause it fall. The said Bell can be made of wood or basket bottoms.

Witnessing that the above is a true specification of my said improvement as above described. I have here set my hand and seal this twenty eighth day of June 1851 the thousand eight hundred and thirty one.
